Application October 1, 1948, Serial No. 52,341

4 Claims. (Cl. 250—41.9)

1

This invention relates to mass spectrometers in general and in particular to improvements therein relating to the formation of an electron beam for the ionization of sample molecules in the mass spectrometer.

A mass spectrometer is an analytical apparatus which functions to sort and measure ions. Ordinarily it includes an ionization chamber into which molecules of the sample to be analyzed are introduced. In the ionization chamber the molecules are bombarded by a stream of electrons and converted into ions. So called propelling or accelerating electrodes propel the ions from the ionization chamber into and through an analyzer chamber.

During passage through the analyzer chamber the ions are subjected to a transverse electric or magnetic field or both, to separate them according to their mass-to-charge ratios into a plurality of diverging beams of ions. Each ion beam is composed of ions of the same specific mass and differing from the mass in the other beams. The diverging beams are successively focused on an ion collector by varying the potential applied to the accelerating electrodes or by varying the intensity of the transverse field in the analyzer tube. The current produced by the discharge of each beam on the ion collector is a measure of the partial pressure of the molecules (from which the ions were derived) in the sample being analyzed.

In one type of mass spectrometer, ions are formed within the ionization chamber by an electron beam directed through the chamber at right angles to the path of the ions. A conventional instrument is equipped with a ribbon filament for the production of electrons which are directed through a slit in the wall of the ionization chamber transversely across the chamber and through a slit in the opposite wall to impinge on an electron collector or target. In this arrangement the ribbon produces an electron beam with a sufficiently large cross section that warpage or movement of the filament still permits the size of the cross section of the beam to be determined by the slit, commonly referred to as the electron slit. The filament is made in the form of a thin ribbon so that an electron beam of large cross section is produced with low end effects by a reasonable length of filament. The thin ribbon also gives a reasonably low power consumption.

I have now found that another possible arrangement is to use a filament of sufficiently small cross section so that the thickness of the

electron beam is determined by the size of the filament rather than by the size of the electron slit. This arrangement has the following advantages over the conventional "electron gun" described above:

1. For the same emission density and the same cross section of the electron beam, the watts consumed by the small filament are less due to the small radiation area;
- 10 2. The filament can be made sufficiently small that reasonable wattage consumption can be obtained when using a filament with a circular cross section. In this respect the circular cross section has the advantage of having a longer life.
- 15 3. The reason for the longer life of a filament with a circular cross section may be appreciated from the following comparison. For example, comparing the life of an 8 mil diameter filament with the life of a 1 by 40 mil flat ribbon filament,
- 20 4. considering that the life is determined by evaporation, it will be seen that the round filament will have a life corresponding to at least one mil evaporation of tungsten. On the other hand, it would probably be necessary to discontinue the
- 25 5. use of the flat ribbon filament after 0.1 mil had evaporated.

There is one problem which becomes more acute, but for which I have provided a simple solution when the physical size of the filament, rather than the size of the electron slit is used to limit the thickness of the electron beam. When the thickness of the beam is to be limited by the size of the filament and where the filament is in a magnetic field of low magnitude, say 500 gauss or less, it is necessary to provide some sort of electric field focusing.

There are many means of obtaining this electric field focusing but a preferred method in accordance with the invention is to mount a shield, either flat or cupped, on the side of the filament opposite the electron slit. By adjusting the voltage on the shield it is possible to drive all of the electrons, emitted from the filament, back into the filament except for a narrow strip on the electron slit side of the filament. At the same time it is possible to produce an electrical field on the emitting side of the filament which is substantially parallel to the desired direction of motion of the electrons or I may produce a field which is slightly converging so that any side energies imparted to the electrons are in such a direction that the thickness of the electron beam is reduced. This latter feature is highly important since any side energies which will thicken the beam and make it larger than the filament

will impair the resolution of the mass spectrometer.

In accordance with the invention therefore, I provide in combination with a mass spectrometer having an ion source comprising an ionization chamber, a slit in a wall thereof for introducing electrons into the chamber and a sample inlet tube, the improvement comprising an electron emitting filament of small cross section, preferably circular, mounted adjacent the ionization chamber and aligned with the slit, and a focusing electrode disposed on the side of the filament opposite the ionization chamber and being at a potential such as to drive the electrons emitted from the filament back into the filament except for a narrow strip on the ionization chamber side of the filament.

As pointed out above, this arrangement serves to determine the dimensions of the electron beam and the size of the slit through the wall of the ionization chamber is no longer critical. The invention will be better understood from the following detailed description thereof taken in conjunction with the accompanying drawings in which:

Fig. 1 is a diagrammatic view of a conventional 180° mass spectrometer showing the ionization chamber end of the instrument blown up to approximately three times its comparative size;

Fig. 2 is a line diagram of the electric field produced by the filament shield and the electron slit when the voltages are properly adjusted.

Fig. 3 is a sectional elevation of an ion source as described by Clifford E. Berry in United States patent application Serial No. 33,596 filed June 17, 1948, showing means of employing the electron source of the invention in conjunction therewith;

Fig. 4 is a section taken on the line 4—4 of Fig. 3; and

Fig. 5 is a perspective view of the electron source of the invention mounted as described by Gordon W. Pallette in United States patent application Serial No. 40,481, filed July 24, 1948.

In the drawings the invention is shown in association with a 180° mass spectrometer of the type wherein propelling electrodes are provided in the ion source. As will be apparent from the following description, the invention is equally adapted to incorporation in substantially any mass spectrometer wherein the sample to be analyzed is ionized by means of an electron beam. The invention is independent of the particular focusing means, the path of ion travel or the use of accelerating electrodes.

Referring to Fig. 1, it will be observed, that it shows a mass spectrometer 10 having an ion source 11, an analyzer tube 12, and an ion collector 13 disposed within an envelope 14 which is kept at low pressures during the operation of the instrument. The analyzer tube 12 is provided at the end adjacent the ion collector 13 with an exit slit 15 through which the ion beams are focused onto the collector 13.

The spectrometer is provided with a pumping system or envelope exhaust line 16 which may be connected with a mercury diffusion pump, molecular pump, or any appropriate evacuating system not shown. The analyzer tube 12 may be provided with ports 17, by means of which the ion source and the analyzer tube are evacuated through the envelope. Alternatively, the envelope may be omitted by making the analyzer tube 12 gas tight and attaching the pumps to it by means which are well known. An inlet line

18 provides means for introducing a sample to be analyzed. An electron gun 20 in accordance with the invention is mounted adjacent to or as part of the ion source and cooperates with an electron target or catcher 21 to discharge a beam of electrons through an electron slit 22 in a wall of the ion source adjacent the gun 20 and a second electron slit 23 in an opposite wall of the source adjacent the collector 21. A propelling electrode 25 and accelerating electrodes 26, 27 are disposed within the ion source so as to propel the ions formed therein into and through the analyzer tube. Representation of this particular ion source is for illustrative purposes only, there being many modifications thereof, equally applicable to this invention.

As above described, the ions propelled from the source are formed in the analyzer tube into diverging beams of ions of given specific mass. These diverging beams are successively focused on the ion collector 13 through the exit slit 15 by varying the potential applied to the accelerating electrodes 26, 27. The ion collector 13 is linked with an amplification and sensing circuit by a lead 29 sealed through the wall of the envelope 13. The lead 29 connects the collector 20 to an amplifier 30 which is in turn linked to a sensing means (not shown) such as a recorder or the like.

Accelerating electrodes 26, 27 are connected through leads 32, 33 respectively to a conventional voltage supply circuit. In a similar manner the propelling electrode 25 and the electron gun 20 and catcher 21 are connected to a more or less conventional voltage supply circuit.

The electron gun 20 shown in Fig. 1 comprises a filament 34 preferably of circular cross section and disposed adjacent the first electron slit 22. An electron shield 36 is disposed adjacent the filament 34 on the side opposite the electron slit 22. A focusing electrode 37 is disposed between the filament 34 and the slit 22 and has a slit 37A therein in alignment with the filament and electron slit 22. By establishing the proper potential between the shield 36, the filament 34, and the focusing electrode 37, the electrons emitted from the filament may be driven back into the filament except for a very narrow beam emanating from the filament from the side adjacent the focusing shield. In this manner, and by making the slit width greater than the filament diameter, the electron beam width becomes independent of the dimensions of the electron slits 22 and 37A.

The electric field established around the filament 34 is illustrated in the line diagram of Fig. 2 showing the filament 34, the focusing electrode 37 and the shield 36. Representative potentials are shown; the shield being at -50 volts, the filament at 0 volts and the focusing electrode at +20 volts. In the drawing of Fig. 2 the shield 36 is shown as a flat surface rather than in the arcuate form shown in Fig. 1. The shield electrode 36 may be either flat or arcuate, the flat form being shown in the diagram of Fig. 2 to simplify the illustration of the field forces set up thereby.

Referring to Fig. 2 it is seen that a portion of the electrons emitted from the filament 34 are driven back into the filament. The phenomena is illustrated by lines 40, 41, 42 etc. Another portion of the electrons emitted from the filament 34 are propelled in the direction of the focusing electrode 37 and converge towards each other. The electric field controlling the motion of the

electrons is represented by the lines 43, 44 and 45. The illustration of Fig. 1 is diagrammatic only in that it does not show specific means for mounting the electron source of the invention with respect to a specific ionization chamber. In Fig. 3 I have shown in sectional elevation an ion source of the type described by Clifford E. Berry in United States patent application Serial No. 33,596, filed June 17, 1948. This particular ion source is chosen as a means of illustrating the application of the electron gun of the invention to an ion source but is not intended to limit the invention in its application to any particular source. As described above, any ion source will comprise a substantially enclosed chamber, commonly referred to as an ionization chamber, having an inlet and an outlet and at least one electrode for discharging ions from the chamber after they have been formed therein. The electron source of the invention is adapted to be employed with any ion source of this nature. In Fig. 5 the electron source is shown in a perspective view as mounted in accordance with mounting means described by Gordon W. Pallette in co-pending United States patent application Serial No. 40,481, filed July 24, 1948.

Referring now to Figs. 3 and 4 it will be seen that the ion source 60 comprises a chamber 61 having an inlet 62. A propelling or pusher electrode 64 is disposed in the inlet end of the chamber 61 which is provided with an exit slit 65 opposite the pusher electrode. Additional electrodes 66, 67, known as accelerating electrodes, are frequently employed to accelerate the ions issuing from the chamber 61 through the slit 65. The means of mounting the various electrodes with respect to the ionization chamber and means of applying differing potentials thereto is described in detail in the aforesaid co-pending application of Clifford E. Berry and forms no part of the present invention.

As shown in Fig. 4 the body of the ion source 60 is generally cylindrical in section. A portion of one wall of the source is cut away to form a flat face 70 extending from the lower end of the ion source (Fig. 3) to a point substantially in lateral alignment with the outlet end of the ionization chamber 61. An arcuate shield 72 forms with the face 70 an enclosure 71 open at its lower end and closed at its upper end by an overhanging lip 73.

The electron source itself (see Figs. 3, 4 and 5) comprises a filament or wire 76 preferably of circular cross section attached at opposite ends to terminal posts 77, 78. Preferably the terminal posts are sprung inwardly a small amount when the wire is affixed to their top end so as to produce an expanding tension on the filament. The terminal posts are sealed through an insulating base 80 and project through the opposite side of the base for connection to suitable electric leads (not shown). A post 82 is sealed in the base 80 intermediate the terminal posts 77, 78, and supports at its upper end (see Fig. 5) a positioning member 84. The positioning member is shaped to fit within a receptacle 86 formed centrally on the flat face 70 of the ion source body. As described in the aforementioned co-pending application of Gordon W. Pallette, by fitting the positioning member within the receptacle and affixing the same thereto the position of the filament is fixed with respect to a first electron slit 94 in a wall of the ion source. A diametrically opposite slit 95 opens into a cavity 96 in which is disposed an electron catcher 98.

As shown in Figs. 4 and 5 and as described by Pallette, the posts 82 upon which the positioning member is mounted is displaced forwardly from the plane intercepting the terminal posts 77, 78. This permits insertion of the positioning member in the receptacle 86 and proper spacing of the filament 76 with respect to its lateral displacement from the wall of the ion source. In accordance with the invention the mounting means is provided with a pair of auxiliary conductive posts 100, 101 sealed through the base and extending parallel to the terminal posts 77, 78 and intermediate these posts and the center post 82. A semi-circular electrode 104 is mounted to the upper end of the posts 100, 101 so as to extend partially around the filament 76.

In this embodiment of the invention the electrical shaping field around the filament 76 is formed by the electrode 104 and by the wall of the ion source 60. The focusing electrode i. e. the electrode 37 (Fig. 1) is omitted. The use of additional focusing electrode is an optional feature of the invention since the ion source itself may be established at a potential such as to accomplish the purpose of the focusing electrode.

As above described the electrode 36 (Fig. 1) or the electrode 104 (Figs. 3, 4 and 5) may be either arcuate in section as shown in Figs. 1, 3, 4 and 5 or it may comprise a flat plate as illustrated schematically in Fig. 2. Referring to the electron source shown in Fig. 5 it will be necessary, if using a flat electrode to replace the electrode 104, to offset the conductive posts 100, 101 rearwardly as viewed in Fig. 5. This may be easily done so as to dispose the flat electrode in a plane lying behind the filament 76 a distance approximately equal to the spacing between the filament and the arcuate electrode 104.

By using an electron source of the type described, regardless of the means by which it is mounted to the ion source or regardless of the type of ion source employed, the dimensions of the first electron slit 94 communicating between the electron emitting filament and the inside of the ionization chamber are no longer critical. Heretofore the shaping of the electron beam has been determined by the dimensions of this slit which were therefore highly critical.

The invention has been illustrated and described with reference to the use of a filament of circular cross section. Although use of such a filament constitutes preferred practice, filaments of irregular section or comparatively narrow ribbon filaments are satisfactory. In any case, filament dimensions should be selected, such that the size of the electron beam will be determined by the filament in association with the shaping field irrespective of the size of the electron slit in the ionization chamber wall.

One feature of the Pallette mounting means which makes it particularly advantageous for use with the electron source of the instant invention is the accuracy with which its positioning may be fixed. Since the character of the electron beam is determined in my electron source by the size of the filament and by the shaping field produced between the shield electrode and the ion source or auxiliary focusing electrode, the positioning of these elements with respect to the ionization chamber or the slit opening thereinto is important. Although Pallette shows one excellent means of establishing a fixed relationship between the electron emitting filament and the ion source as such, any such means are within the contemplation of the invention.

1. **Claim:**

1. In a mass spectrometer ion source for use in a relatively weak magnetic field, the combination comprising an ionization chamber having a slit in a wall thereof for admitting a beam of electrons into the chamber, an electron emitting filament of smaller cross section than the minor axis of the slit opening mounted adjacent the ionization chamber and in alignment with the slit, and means for producing a shaping electrical field around the filament to form the electrons emitted from the filament into an electron beam of smaller cross section than the slit and directed through the slit.

2. In a mass spectrometer ion source for use in a relatively weak magnetic field, the combination comprising an ionization chamber having a slit in a wall thereof for admitting a beam of electrons into the chamber, an electron emitting filament of circular cross section and of smaller diameter than the minor axis of the slit opening mounted adjacent the ionization chamber and in alignment with the slit, a semi-cylindrical electrode mounted coaxially with the filament and on the side thereof opposite the ionization chamber, and means for impressing a potential on the electrode to direct the electrons emitted by the filament through the slit as a beam of smaller cross section than the slit opening.

3. In a mass spectrometer ion source for use in a relatively weak magnetic field, the combination comprising an ionization chamber having a slit in the wall thereof for admitting a beam of electrons into the chamber, an electron emitting filament of smaller cross section than the minor axis of the slit opening mounted adjacent the chamber and in alignment with the slit, and means for producing a shaping electrical field

around the filament to form the electrons emitted from the filament into an electron beam of smaller cross section than the slit and directed through the slit.

4. In a mass spectrometer ion source for use in a relatively weak magnetic field, the combination comprising an ionization chamber having a slit in a wall thereof for admitting electrons into the chamber, an electron emitting filament of smaller cross section than the minor axis of the slit opening mounted adjacent the ionization chamber and in alignment with the slit, a first electrode spaced from the filament on the side opposite the ionization chamber, a second electrode disposed between the filament and the ionization chamber and having a slit therein in alignment with the slit in the ionization chamber and defining an opening having a minor axis longer than the cross section of the electron emitting filament, and means for impressing a potential between the first and second electrodes to shape the electrons emitted from the filament into a beam directed through the slits in the second electrode and in the ionization chamber and of a width independent of the dimensions of the slits.
